UNITED STATES PATENT OFFICE.

JOHN H. LANGE, OF MUSCATINE, IOWA, ASSIGNOR OF ONE-HALF TO WILLIAM H. SCHWAB, OF MUSCATINE, IOWA.

EMERGENCY DRAFT-WINDLASS.

1,229,762.

Specification of Letters Patent. Patented June 12, 1917.

Application filed July 28, 1916. Serial No. 111,855.

To all whom it may concern:

Be it known that I, JOHN H. LANGE, a citizen of the United States, residing at Muscatine, in the county of Muscatine and 5 State of Iowa, have invented certain new and useful Improvements in Emergency Draft-Windlasses, of which the following is a specification.

This invention relates to windlasses.

10 The invention has more especial reference to an improved device of the character stated which is portable in nature and has for its primary object, the provision of pulling means which may be readily attached to a driving wheel of a motor vehicle, whereby, the same may be used to assist in pulling the vehicle out of ruts, mud, etc. Specifically speaking the invention may be stated to provide an emergency draft 15 windlass.

More particularly, the present invention has reference to a novel construction and arrangement of various constituent parts of the device, means being provided whereby 20 the device may be so adjusted as to be adapted for use upon wheels of large and small wheel base and further, means being provided which means are carried by the adjusting means, whereby the device may be 25 securely affixed to the particular wheel to which it is applied.

Another important characteristic of the present invention, resides in the simplified construction, which will consequently, reduce the cost of manufacture of construction 30 of this character, and further, the provision of novel details in the construction and arrangement of parts with a view to higher efficiency generally.

40 All of the foregoing, together with additional advantageous details and arrangement of parts of the preferred embodiment of my invention will be clear from the specific description hereinafter contained, when read 45 in connection with the accompanying drawings forming a part thereof, wherein said embodiment of the invention is illustrated for the purpose of facilitating a full understanding of the present improvements.

50 In the drawings:—

Figure 1 is a side elevation showing my improved device applied to a wheel;

Fig. 2 is a side elevation of the device detached;

Fig. 3 is a transverse section therethrough; 55 and

Fig. 4 is a section taken on line 4—4 of Fig. 2.

Referring now more particularly to the drawings wherein like reference characters 60 designate like or corresponding parts throughout the several views, it is to be understood, at the outset that the device may be applied to any size or form of motor vehicle driving wheel and for the purpose 65 of convenience, I have indicated a wheel which is designated by the numeral 1.

A sleeve or drum 2 having a flange 3 formed upon its outer marginal edge and a base portion whereby the same may be 70 attached to the wheel, which shall be hereinafter described is provided. A base portion or laterally offset portion 4 is arranged upon the opposite extremity of the sleeve 2 and has arranged thereupon, a plurality 75 of fingers generally designated at 5. Undercut ways 6 are formed in each of these fingers 5 and are disposed substantially longitudinally thereof. Sliding elements or arms 7 provided with beveled sides 8 and 80 8' are receivable by the undercut ways 6, the beveled side portions thereof engaging the undercut walls of the way so as to prevent outward lateral movement of the arms 7.

In order that the arms 7 may be securely held in an adjusted position within their respective ways, set screws generally numbered 9 are received in complementally threaded openings arranged adjacent the outer extremities of the fingers 5 and communicating with the ways 6. Thus, when the set screws are turned inwardly, it will be obvious, that the same are engaged with the under face of the sliding arms 7, thereby, 85

serving as means to bind them in their respective way and consequently, prevent further longitudinal movement thereof. T-shaped openings are arranged in the outer extremities of the sliding arms 7, the vertical portions thereof being interiorly threaded so as to receive set screws 10, which set screws serve as means to lock the spoke engaging hook 11 in an adjusted position within the transverse portion of the opening. 90

A plurality of laterally extending fingers 105 12 are secured to the inner side of the base portion 4 and engage with the adjacent spokes of the wheel 1 whereby, relative ro-

tary movement of the sleeve 2 with relation to the wheel 1 will be prevented.

A cable *a* having one end thereof secured to the sleeve 2 is coiled thereabout and has arranged upon its remaining end a hook or other suitable engaging member, not shown.

In operation, the various sliding arms 7 are adjusted to the desired position, whereupon the hooks 11 are engaged with the various adjacent spokes of the wheel and when engaged, are securely locked in position by means of the set screws 10. It will be also obvious, that as the device is applied over the hub of the wheel, the laterally extending fingers 12 will abut those spokes as engaged by the hook 11 and thereby, prevent relative movement of the windlass and the wheel. Due to the fact that the sleeve 2 is arranged about the hub of the wheel, it will be readily understood, that the same is efficiently supported in position and that the hub will further serve as means to compensate for the strain to which the spool is subjected, when in use. With the windlass in the proper position upon the wheel, the cable *a* is uncoiled, and the engaging member as secured to the rear extremity thereof is engaged with a stationary object at a distance from the vehicle. The motor of the vehicle is then started and power is transmitted to the driving wheel, which, when rotated by means of its engagement with the cable, will be caused to be moved forwardly and thereby permit the coiling of the cable about the sleeve 2. When the vehicle has been assisted out of the rut, the windlass may be then quickly detached, the engaging member removed from the stationary object and the device as a whole may be then placed in some suitable support therefor as carried by the vehicle.

It is obvious that changes may be made without departing from the spirit of the invention so long as they fall within the scope of the appended claims.

I, therefore, particularly point out and distinctly claim as my invention:

1. An attachment for driving wheels of motor vehicles, comprising a drum, an enlarged head portion having a plurality of radially disposed ways formed in one face thereof arranged adjacent said drum, a plurality of laterally extending fingers arranged on the head portion, arms slidably arranged in said radially disposed ways, means for securing said arms in adjusted positions in the radially disposed ways, and

spoke engaging hooks carried on the outer ends of said arms.

2. An attachment for driving wheels of 60 motor vehicles comprising a cable winding drum having a plurality of radially extending fingers arranged adjacent one end thereof, slideable arms carried by the fingers, and laterally adjustable hooks arranged adjacent the outer extremities of said slideable arms for securing said drum to the wheel. 65

3. An attachment for driving wheels of 70 motor vehicles, comprising a cable winding drum, a plurality of radially extending fingers arranged adjacent one extremity of said drum, slideable arms carried by said fingers, means for securing said arms in an adjusted position, laterally adjustable hooks 75 carried by the outer extremities of said arms, and means for securing said hooks in an adjusted position.

4. An attachment for driving wheels of 80 motor vehicles, comprising a cable winding drum, a plurality of radially extending fingers arranged adjacent one extremity of 85 said drum and having longitudinally disposed undercut grooves formed in one face thereof, slideable arms receivable by said undercut grooves, set screws for securing 90 said arms in an adjusted position, laterally adjustable hooks carried by the outer extremities of said arms for engagement with the spokes of the wheel, and set screws engageable with portions of said hooks whereby the same may be secured in an adjusted position. 95

5. An attachment for driving wheels of 100 motor vehicles, comprising a cable winding drum, a plurality of radially extending fingers arranged adjacent one extremity of 105 said drum, longitudinally disposed undercut grooves formed in one face of said fingers, slideable arms receivable by said undercut grooves, set screws for securing said arms in an adjusted position, laterally adjustable hooks carried in the outer extremities of said slideable arms, means for securing said hooks in an adjusted position, and a plurality of distended spoke abutting fingers arranged adjacent said laterally distended fingers for preventing relative movement of the drum.

In testimony whereof I affix my signature in presence of two witnesses.

JOHN H. LANGE.
